United States Patent Office.

LEWIS RATHBONE, OF ALBANY, NEW YORK.

Design No. 2,650, dated May 7, 1867.

DESIGN FOR A WOOD-STOVE.

The Schedule referred to in these Letters Patent and making part of the same.

Be it known that I, LEWIS RATHBONE, of the city of Albany, State of New York, have produced a new and original Design for a Wood-Burning Stove; and I declare the annexed drawing, exhibiting the said stove in perspective, to be a complete and accurate description and delineation of the ornamental design thereof, the ornamental parts not shown by the perspective being similar and symmetrical with the parts shown.

What I claim, and desire to secure by Letters Patent, is—

The design for the above stove, as shown and described.
